UNITED STATES PATENT OFFICE.

JACOB NEY, OF CANTON, OHIO, ASSIGNOR TO THE V. L. NEY COMPANY, OF CANTON, OHIO, A CORPORATION OF OHIO.

HAY-ELEVATOR.

SPECIFICATION forming part of Letters Patent No. 690,660, dated January 7, 1902.

Application filed October 3, 1901. Serial No. 77,396. (No model.)

To all whom it may concern:

Be it known that I, JACOB NEY, a citizen of the United States, residing at Canton, in the county of Stark and State of Ohio, have invented certain new and useful Improvements 5 in Hay-Elevators; and I do hereby declare that the following is a full, clear, and exact description of the same, reference being had to the annexed drawings, making a part of this specification, and to the figures of reference marked thereon, in which—

Figure 1 is a side elevation showing the carriage locked upon the track or way. Fig. 2 is a vertical section showing the carriage locked to the track or way. Fig. 3 is an end view of the carriage, showing a transverse section of the track or way and illustrating the trip-bar placed in operative position. Fig. 4 is a detached view of the carriage-releasing lever. Fig. 5 is a detached view of the upper or stop-block-engaging dog. Fig. 6 is a detached view of the push dog or head. Fig. 7 is a detached view of the interposed carriage-releasing and rope-grip-operating device. Fig. 8 is a detached view of the rope-gripping shoe. Fig. 9 is a detached view of the lower or register-head-engaging dog.

The present invention has relation to hay-elevators designed and arranged to release 30 the carriage from a fixed point upon the track or way at any point between the starting and stopping point of the load to be elevated and to release the carriage from the track or way when the register-head has become connected 35 with the carriage; and the invention consists in the different parts and combination of parts hereinafter described, and particularly pointed out in the claims.

Similar numerals of reference indicate corresponding parts in all the figures of the drawings.

In the accompanying drawings, 1 represents the track or way, which is supported in an elevated position in the usual manner and 45 upon which track or way the carriage travels back and forth over the place or places where it is desired to deposit or drop the loads to be elevated and deposited.

The carriage proper, as shown, is formed 50 of two sections 2 and 3, which sections are swiveled together by means of the tongue and

groove 4; but the purposes of the present invention can be carried out without any reference to the exact construction of the frame of the carriage. I have, however, illustrated 55 a reversible carrier or one designed to deposit the loads elevated upon either side of a driveway, which driveway usually consists of the ordinary barn-floor, with mows located upon opposite sides thereof.

To the track or way 1 is connected, in any convenient and well-known manner, the stop-block 5, which stop-block may be provided with an integral hanger portion 6; but this is not necessary unless it is desired to support 65 the track above the stop-block.

To the lower section 3 of the carriage-frame are pivotally connected the dogs 7 and 8. The dog 7 is calculated to engage with the stop-block 5 and is brought into the position illustrated in Fig. 2 when the carriage is locked upon the track or way. The dog 8 is located below the dog 7 and in operative contact with the dog 7. The dog 8 is provided with the register-head-engaging hook 9. The interposed carriage-releasing device is located between the pivotal points of the dogs 7 and 8, and it consists of two parallel bars 10 and 10^a, spaced from each other by cross-bolts or rivets 11, 12, 13, and 14.

To the lower member of the carriage-frame 3 is pivotally connected the push-dog 16, which push dog or head is pivotally connected to the cross-bolt or rivet 11 of the interposed carriage-releasing device. The push dog or head 85 16 is provided with the arm 17, to which arm are connected the elevating-rope-connecting link or eye 18 and the elevating-rope 19, connected to the link or eye, which elevating-rope extends downward and under the elevating-block 20, and thence upward over the pulley 21, and thence to the point where draft is to be applied. It will be understood that the pulley 21 is to be properly journaled upon a suitable shaft 22, which shaft is connected 95 to the lower member of the frame 3.

To the side of the lower member 3 of the carriage is pivotally connected the carriage-releasing lever 23, which carriage-releasing lever is substantially of the form shown in 100 Fig. 4, and, as shown, its inner upper end is provided with the antifriction-roller 24, which

antifriction-roller is located against the edge of the stop-bar 15 of the carriage-releasing device when said lever is in its normal position or in the position to hold the carriage locked upon the track or way. The stop-bar 15 extends from one of the parallel bars of the carriage-releasing device and is located adjacent to the inner end of the releasing-lever 23.

The carriage-releasing lever 23 is preferably 10 extended downward from its pivotal point, so as to bring it in better position to be operated by the trip-bar 25, which trip-bar is operated by means of the trip-rope 26, which trip-rope extends upward over a pulley 27 and 15 is connected to the trip-bar 25 in any convenient and well-known manner.

The trip-bar 25 is pivotally connected at its outer end, so as to give said trip-bar a horizontal swinging movement, and thereby insure 20 the passage of the carriage back and forth upon the track or way without any interference with said trip-bar.

I do not desire to be confined to the exact arrangement of the trip-bar 25 shown in the 25 drawings, as the only object of said trip-bar is to provide one means of elevating the carriage-releasing lever 23, as it will be understood that the carriage-releasing lever may be elevated to release the carriage in many 30 ways; but I have illustrated one means for elevating the lower end of the carriage-releasing lever for the purpose of showing how said lever may be elevated to release the carriage.

When the carriage-releasing lever is in the 35 position illustrated in Fig. 1, the interposed carriage-releasing device is locked against end movement, and at the same time said interposed carriage-releasing device is held in a position to hold the brake-shoe 28 out of 40 contact with the elevating-rope 19, so that said elevating-rope is free to move around the pulley 21 in the ordinary manner. The brake-shoe 28 is pivotally attached to the parallel members 10 and 10^a of the carriage-releasing device.

It will be understood that when the carriage-releasing device, consisting of the parallel bars 10 and 10^a, is held against end movement the downpull of the elevating-rope 19 50 upon the link 18 will not permit any independent movement of the push dog or head 16, and when the register-head 29 is to be engaged with the hooked end of the dog 8 there is no movement of the interposed carriage-releasing device; but said device re-

55 mains at rest at all times until the lower end of the carriage-releasing lever is elevated; but when the lower end of the releasing-lever 23 is elevated its upper end, which is provided 60 with the antifriction-roller 24, is lowered, so as to bring it out of contact with the bar 15, so that the interposed releasing device is free to move toward the pulley 21 and clamp the elevating-rope 19 between the shoe 28 and the 65 pulley 21. The moment the interposed releasing device is freed by elevating of the lower end of the release-lever 23 and lower-

ing the inner upper end thereof the downpull of the elevating-rope will lower the arm 17, which in turn moves the dog 8 upon its pivotal point and brings the upper end of the dog 8 from under the antifriction-roller 30, which antifriction-roller is journaled to the dog 7. As the push dog or head 16 is moved toward the pulley 21 it moves the dog 8 by 70 means of the cross-bolt or rivet 12, and for the purpose of insuring the proper movement of the dog 7 to release the carriage from the stop-block 5 said dog is provided with the downward-extending arm 31, which downward-extending arm is so located that the bolt or rivet 13 will swing the downward-extending arm 31, by which arrangement the movements of the dogs 7 and 8 are made positive and certain. When the dogs 7 and 8 80 have been moved by the forward movement of the carriage-releasing device, the dog 7 will be brought into a position to be released from the stop-block 5, at which time the carriage is free to move upon the track in the direction of the pull of the elevating-rope, and when the carriage is returned the stop-block 5 will bring the dog 7 into proper position to lock the carriage upon the stop-block, and the downward-extending arm 31 will move the 85 interposed releasing device away from the elevating-rope and release the dog 8, so that its top or upper end will come under the friction-wheel 30 of the dog 7, as illustrated in Fig. 2, and allow the inner upper end of the 90 lever 24 to move upward, so as to bring the antifriction-roller 24 directly in front of the cross-bar 15.

It will be understood that the lower end of the lever 23 should be of such a weight that 95 it will fall by gravity when the bar 15 is brought from under the upper end of said lever.

It will be understood from the above description that when the carriage-releasing lever 23 is elevated at its bottom or lower end the carriage will be released from the stop-block upon the track or way regardless of the register-head 29 and that it is immaterial as to the location of the register-head or the load 110 being elevated, so that by my peculiar arrangement I am enabled to release the carriage and lock the elevating-rope to the carriage at any desired time during the elevation 115 of the load and before the register-head 29 has 120 become engaged with the carriage.

If it is desired to engage the register-head with the carriage and lock the load to the carriage, no attention is paid to the trip-rope 26, and no independent movement is imparted to 125 the lever 23 or to the carriage-releasing device, consisting of the parallel bars 10 and 10^a, and no independent movement is imparted to the push dog or head 16; but the dogs 7 and 8 are operated by the register-head 29 130 coming in contact with the bottom or under side of the arm 39 of the dog 8, which elevates said arm, throwing the upper end of the dog 8 from under the dog 7, which releases said

dog from the stop-block 5. The operation just above described is the ordinary operation and the same that it would be without the interposed releasing device, consisting of 5 the parallel bars 10, the lever 23, and a trip-bar or other device to lift the carriage-releasing lever 23.

For the purpose of providing a means for holding the forward ends of the parallel bars 10 in proper relative position the lugs 33 are provided, which lugs are located directly under said parallel members 10.

For the purpose of allowing the rope-clamping shoe 28 to have a yielding movement between the parallel bars 10 and itself said shoe is pivotally attached to said bars.

Having fully described my invention, what I claim as new, and desire to secure by Letters Patent, is—

20 1. In a hay-elevator, a track or way, a traveling carriage mounted upon the track or way, a stop-block fixed to the track, a dog adapted to lock the carriage to the stop-block, and a register-head-engaging dog, a register-head 25 engaging the dog and a carriage-releasing device located intermediate the dogs, said releasing device provided with a brake-shoe, substantially as and for the purpose specified.

2. In a hay-elevator of the class described, 30 a track provided with a stop-block, a carriage movable thereon, dogs carried by the traveling carriage, a carriage-release lever pivotally connected to the carriage-frame, parallel bars provided with a stop-bar, a rope-clamping shoe pivotally connected to the parallel bars and a push dog or head connected to and carried by the parallel bars; and an elevating-rope suspended from the push dog or head, substantially as and for the purpose specified.

35 3. In a hay-elevator the combination of a track or way provided with a stop-block, a carriage located thereon, said carriage provided with a release-lever and means for releasing the lever from engagement with the 40 interposed carriage-releasing device, a dog adapted to lock the carriage in fixed position upon the track independent of the register-head-engaging dog, and an interposed carriage-releasing device, substantially as and 45 for the purpose specified.

4. In a hay-elevator, the combination of a track or way, a traveling carriage mounted upon the track or way, dogs adapted to lock the carriage and registering head, said dogs 50 located in operative position with each other and independent of the interposed carriage-releasing device, a stop-block located upon the track or way, and an interposed carriage-releasing device, substantially as and for the 55 purpose specified.

5. In a hay-elevator the combination of a track or way provided with a stop-block, a carriage-locking dog carried by the carriage and provided with a downward-extending arm, sliding parallel bars spaced one from 60 the other and provided with a bolt or rivet adapted to engage the downward-extending arm of the carriage-locking dog, a push dog or head pivotally connected to the carriage and to the spaced parallel bars, one end of the 65 elevating-rope suspended from the push head or dog, and a registering-head-engaging dog and a pivoted lever carried by the carriage-frame and adapted to lock the parallel bars against end movement, substantially as and 70 for the purpose specified.

6. The combination of a traveling carriage mounted upon a track or way, a stop-block fixed to the track or way, a dog carried by the carriage to engage the stop-block and lock 80 the carriage, a register-head-engaging dog carried by the carriage and in operative position with the carriage-locking dog, and the dogs adapted to operate with contact with the registering head and independent of the interposed carriage-releasing device, and an interposed carriage-releasing device substantially as and for the purpose specified.

7. The combination of a track or way provided with a stop-block, a carriage mounted 90 thereon and provided with a carriage-locking dog and a register-head-locking dog, and an interposed carriage-releasing device provided with a push-dog and an elevating-rope-clamp shoe carried by the interposed carriage-releasing device, and a lever adapted to lock the carriage-releasing device against end movement and to release the interposed releasing device, substantially as and for the 95 purpose specified.

8. The combination of a track or way provided with a stop-block, a carriage mounted thereon, means for locking the carriage to the stop-block, a sliding carriage-releasing device adapted to be operated by the down-pull of the elevating-rope to release the carriage and lock the elevating-rope, and a lever carried by the carriage adapted to lock the carriage-releasing device when in normal position and to release the carriage from the 105 track or way and lock the elevating-rope when out of normal position, substantially as and for the purpose specified.

In testimony that I claim the above I have hereunto subscribed my name in the presence 110 of two witnesses.

JACOB NEY.
